Attorney

UNITED STATES PATENT OFFICE.

SIGFRED BECH, OF TOTOWA, NEW JERSEY.

BOWLING ALLEY.

1,409,274.

Specification of Letters Patent. Patented Mar. 14, 1922.

Application filed April 12, 1921. Serial No. 460,778.

To all whom it may concern:

Be it known that I, SIGFRED BECH, a citizen of the United States, residing at Totowa, in the county of Passaic and State of New Jersey, have invented a certain new and useful Improvement in Bowling Alleys, of which the following is a specification.

This invention relates to improvement in what are termed bowling alleys, more especially the sectional or foldable type.

The invention has for its object to provide for readily folding the instrument or device with facility and compactly to promote portability or transportation of the same; also to simplify structure and lessen the number of parts; also to improve the plan of operation or method of use of the device.

Other objects of the invention will be apparent from the following description of the construction and arrangement of the parts, and the carrying out of the aforesaid outlined features thereof.

The invention consists therefore of certain instrumentalities and features of construction substantially as hereinafter more fully disclosed and defined by the appended claims.

The accompanying drawings illustrate the preferred embodiment or one form of my invention wherein it will be understood that various changes and modifications as relate to the detailed construction and arrangement of parts may be made without departing from the spirit or scope thereof as covered by the claims, and in which drawings—

Figure 1 represents a plan view of my invention in extended or usable condition.

Figure 2 is a side view thereof.

Figure 3 is a view in side elevation showing the device folded.

Figure 4 is a transverse section taken on the line 4—4 of Figure 3.

Figure 5 is a transverse section taken on the line 5—5 of Figure 1.

As characteristic features of my invention, I form the same, bodily, of a multiple or plurality of sections 1, preferably three, said sections being rectangular in general outline and foldable superposedly with respect to each other as indicated in Figures 3 and 4. Each section is preferably formed of duplicate lateral members 1^a and a bottom-forming member 1^b preferably mortised and tenoned about centrally to the lateral members, or the same may be otherwise carpen-

tered together. The sections are connected together preferably by hinging or articulating the lateral members at the diagonally opposite edge thereof at their meeting ends as at 2 particularly as seen in Figures 2 and 3 providing for the alinement of the sections when extended for use as indicated in Figures 2 and 3. The bottom-forming members 1^b of the multiple or plurality of sections 1 are each formed with opposite spaced-apart longitudinal grooves or gutters 3, adjacent the lateral members 1^a thereof, the grooves or gutters of a bottom-forming member being arranged to aline the respective grooves of the other members 1^b of the sections 1, the purpose of which will be apparent later. Within the grooves 3 are arranged resilient metal members or stops 4 suitably secured or driven into the bottom-forming member of the device, adjacent the pin-positioning, or "pit", end 5 thereof, as seen particularly in Figures 1, 2 and 5. The lateral members 1^a of the sections 1 are equipped with sections 1^c and elastic buffer-members 1^d along their longitudinal edges, respectively, for suitably superposing or cushioning these noiselessly one upon the other, as seen in Figure 4. Also these sections may be provided at their meeting edges with suitable interfitting joint-forming tenons and mortises 1^e, 1^f respectively as means for the reinforcing or strengthening the articulating or hinging connections between said sections when in extended position.

It will be observed that, in using the device, in the event of the player making a "puddle," as called in bowling-alley parlance, or terminology, a thrown ball, taking an erratic or stray course, resulting in its entering one of the grooves or gutters 3, it will be intercepted by the resilient member, and, by the resiliency of the latter be automatically returned, via the groove or gutter 3, to the player, providing for expediting the throw of the recalcitrant ball as would not be the case otherwise as will be readily appreciated.

In the pit-end 5 of the device, into which are stored the pins 6 and balls 7, when not in use, is inserted a partition 8 adapted to provide for forming the "pit" and for the retention of the pins and balls in restricted position as against shifting casually back and forth within the device when the latter is handled or moved about from place to place or transported.

Suitable fastening means, as hooks and screw-eyes 9, 9^a or otherwise are provided upon the respective sections 1 at the required points, for suitably holding the latter in compactly folded position as seen in Figures 3 and 4, also in extended position as seen in Figures 1 and 2, as circumstances may be desired.

I claim and desire to secure by Letters 10 Patent of the United States:

1. A device of the type described, including an instrumentality complementary to a bowling alley outfit and having opposed longitudinal ball-receiving grooves 15 and resilient stops arranged in said ball-receiving grooves, and adapted to function with and automatically return an erratically thrown or stray ball to the player.

2. A device of the type described, including an instrumentality complementary to a bowling alley outfit and comprising a multiple of foldable sections having opposed longitudinal ball-receiving grooves, and resilient stops arranged in said ball-receiving 25 grooves and adapted to function with and automatically return an erratically thrown or stray ball to the player.

3. A device of the type described, including an instrumentality comprising a multiple of foldable sections complementary to a bowling-alley outfit, said foldable sections having opposed longitudinal ball-receiving grooves, and resilient stops arranged in said ball-receiving grooves, said grooves 35 each adapted to receive an erratic-thrown

or stray ball and said resilient stop adapted to automatically return the ball via one of said grooves to the player.

4. A device of the type described, including an instrumentality comprising a multiple of foldable, longitudinally grooved sections, complementary to a bowling-alley-outfit, one of said foldable sections having a pit adapted to receive the balls and pins of the latter, and comprising a portable partition or septum for use when the device is being transported, handled or moved from place to place and adapted to be displaced when the device is to be used the grooves of said grooved sections having resilient stops 50 arranged therein to function with and automatically return the balls to the player.

5. A device of the type described, including an instrumentality comprising a multiple of foldable longitudinally grooved sections complementary to a bowling-alley-outfit, one of said foldable sections having a pit adapted to receive the pins and balls of the latter and comprising a displaceable partition or septum, and resilient stops 60 arranged in the grooves, each of said grooves being adapted to receive a stray ball and said resilient stop adapted to automatically return the ball to the player.

In testimony whereof, I affix my signature, in the presence of two witnesses.

SIGFRED BECH.

Witnesses:

ROBERT J. VAN HOUTEN,
FRED VREELAND.
